FUR SCRAPING AND FLESHER APPARATUS

Mike G. Hadgeoff, New York, and Isadore Reiffel,
Mount Vernon, N. Y.

Application May 4, 1932, Serial No. 609,320

10 Claims. (Cl. 149—18)

This invention relates to apparatus for the fleshing and scraping of fur skins, as well as for the performance thereon of other related operations, such as shaving and plucking; one of its 5 main objects being to enable an operator at all times to readily control and adjust the relative positions of the operating tool and the pelt so as to produce uniform and effective results.

In most devices of this class, the skin is placed 10 upon and strapped to a cylindrical base, the tool being operatively movable along the surface of the skin either by manual or mechanical means. The base is made rotatable and movable longitudinally in a direction parallel to its axis, so as 15 to expose every portion of the pelt to the action of the tool; and it is also movable upwardly towards said tool to vary the pressure thereof upon the skin in accordance with the nature of the operation or with the varying conditions and 20 characteristics of different portions of each piece of skin. These movements are generally accomplished by the manipulation of several handles, levers and treadles,—frequently making such a device cumbersome, difficult to operate, and requiring great skill and considerable caution in 25 getting the proper coordination between hand, foot and eye, and necessitating a rare degree of steadiness to maintain, throughout each stroke of the tool, constant and unvarying pressures. 30 We have therefore conceived this invention to overcome these defects by producing a base capable of universal movement, adjustable by hand, and provided with means to adjustably hold it locked in a set position during the operating 35 stroke. Other features, objects and advantages will appear from the drawings, and the description hereinafter given.

Referring to the drawings,

Figure 1 is a side view of the assembly containing our invention; Figure 2 is sectional plan of Figure 1 taken along line 2—2; and Figure 3 is a side section of a portion of the apparatus taken along line 3—3 of Figure 2.

Figure 4 is a section, taken along line 4—4 of 45 Figure 3, of the locking member adapted to hold the base against rotary and longitudinal movement.

Figure 5 is a fragmentary perspective of the 50 lifting lever locking member adapted to hold the base against upward movement during the operating stroke of the tool.

Figure 6 is a front end view of the apparatus; and Figure 7 is an enlarged front end view of 55 the base or skin support, the full line view showing it in one extreme revolved position, and the dot-dash lines indicating the opposite extreme position thereof.

Figure 8 is vertical section of the rear of the 60 apparatus, showing the cam and levers for lock-

ing the base against movement during the operating stroke of the tool.

Figure 9 is fragmentary sectional plan taken along line 9—9 of Figure 1, showing the stroke adjusting mechanism of the tool carrying member; and Figure 10 is an enlarged view of the slotted connection, taken along line 10—10 of 65 Figure 9.

Figure 11 is a perspective of a portion of the tool carrying and guiding linkage; showing the 70 tool-carrying member and the toggle arrangement connecting it to the said linkage.

Figure 12 is a section through the slotted portion of an arm in the parallel motion linkage, taken along line 12—12 of Figure 1; and Figure 75 13 is a fragmentary section of Figure 12 taken along line 13—13.

In the drawings, the frame 15 has rotatably mounted thereon two shafts supported by bearings 16 and 17 respectively, the former shaft carrying the pulleys 18 and 19 and the fly wheel 20, and the latter the cam plate 21. The arm 22 of said fly wheel contains the slotted aperture 23, the walls of which have the notches or serrations 24 therein in parallel alignment with the corresponding notches 25 in the adjacent slotted aperture 26 at the terminal of the substantially horizontal tool-actuating member 27. This latter member is pivotally connected, through the bifurcated end piece 28, to the bracket 29, the upper portion of which contains the pin 30 upon which is pivotally mounted the bar 31, through its end piece 32; and the lower portion containing the pin or bolt 33 upon which is pivotally mounted the tool-carrying member 34, the tool or curved blade 35 being suitably secured thereto. It will be noted that the said bracket 29 contains the recess or opening 36, to accommodate the end piece 32 between its lateral walls. 95

Coextensive with bracket 29 is the extension 37 which contains the adjusting screw 38, the terminal of which is adapted for abutment with the boss 39. The combination of the member 27, the bracket 29 and the bar 31, together with their connecting parts, form a toggle the constituent parts of which are substantially in fixed relation to each other on the power or operating stroke (in the direction of the arrow, Figure 1), due to the contacting of said screw 38 and the boss 39 which holds said parts against further outward movement; but on the return stroke, the toggle is collapsible inwardly, so that should there be any wrinkles or upwardly protruding portions of the skin 40 contacting with the blade 35 on its return stroke, there will be no harm done to the skin, as the toggle will give and the blade will pass harmlessly over any obstacles on said skins. 110

The pivotally connected links 41 and 42 are of such lengths that they will coact with members 27 and 31 to produce a motion of the tool 35 in 115 120

- a direction substantially parallel to the surface of the fur support or base 43, or to the axis of the cylinder of which a peripheral portion constitutes the said base 43. The said link 41 contains the slotted aperture 44 the walls of which have the notches 45 therein in parallel alignment with the corresponding notches 46 in the adjacent slotted aperture 47 in the forward portion of the frame 15.
- 10 Movable within each of said slots 44 and 47 are the notch-engaging members 48 and 49 respectively, these members being shown square in cross-section and having two of their diametrically opposed lateral edges engaging oppositely positioned notches. The said members are rotatably mounted over the shank of the bolt or pin 50, the head 51 thereof and the nut 52 at the opposite extremity thereof holding the said members secured in place within the slotted apertures,—and yet not preventing the pivotal movement of the link 41 about said pin. Similarly, the notch-engaging members 53 and 54 are movable within the slots 23 and 26 respectively, these members having lateral corners engageable within notches in said recesses, and being likewise pivotally mounted over a pin 55. One extremity of said pin extends through the slot 56 in the cam 21 and is operatively engageable therewith. The said notch-engaging members 53 and 54 are yieldably held against lateral movement and in place within the slotted apertures by the nut 57 and washer 58 at one end of the pin, the spacer 59 between the two said slotted apertures, and the spring 60 operating on two washers placed contiguous to the slots 56 and 26.
- 15 Engageable with the periphery of the cam 21 is the follower 61 pivotally attached to the arm 62 which is shown integral with the hub 63 affixed to the shaft 64 by the pin 65. The collar 66, similarly attached to the said shaft 64 by the pin 67, contains the lug 68; the lug 69 integral with the collar 70 which is rotatably mounted over the shaft 64, extending outwardly opposite the lug 68 to accommodate, between said lugs, the helical spring 71. (See Figure 8.) Extending through said lugs and said spring is the bolt 72, which is held in place by the nut 73. The arm 74 (Figure 3), shown integral with the collar 70, extends downwardly, and has at the lower end thereof the slot 75, with which the pin 76 is slidably and operatively engageable, said pin extending through the bifurcated extremity 77 of the chuck control rod 78 which is attached to the central conical member 79 of the chuck mechanism containing the four wedges 80. The outer surfaces of said wedges are frictionally engageable with the inner walls of the cylindrical housing 81 which is mounted upon the tube 82 and upon which is affixed the supports 83 and 84 for the base 43.
- 20 Positioned over the rod 78 is the helical spring 78a, one end of which abuts against the end wall 82a of the tube 82, the other end abutting against the collar 78b affixed to the rod 78.
- 25 Connected to the collar 63 is the lift control arm 85 which is operatively connected, by the link 86 to the cam 87 rotatably mounted on the shaft 83. (See Figure 5.) The end surface of said cam 87 is yieldably kept in frictional engagement, by the spring 92, with the contiguous end surface of the boss 89 secured to or forming an integral part of the framework of the apparatus. The said end surfaces contain complementary recesses and protruding portions, the recess of one being in engagement with the protruding portion of the other in the inoperative position of the parts, and the two protruding portions being in engagement in their operative position. The bell-crank or lever 90 is integral with the sleeve 91 rotatably mounted over the said shaft 88, said sleeve serving also as an abutment for the spring 92.
- 30 The bracket 93 is pivotally attached to the end of the arm 94, and is surmounted over and attached to the tube 82. Another lever 95 is integral with the sleeve 96 (Figures 1 and 2) which is rotatably mounted over the shaft 97; and pivotally connected to the end of the arm 98 is the bracket 99 surmounted over and attached to the tube 82. The link 100 pivotally connects the extremities of the arms 101 and 102 of said levers.
- 35 Positioned over the fur piece 40 is the flexible band 103 (Figures 1, 3 and 7), which may be of steel, and this extends around the suitably mounted block 104, which may have a steel facing 105 on its upper surface for frictional contacting with the protruding element 106 of cam 107. The crank handle 108 attached to this cam is also frictionally engageable with the flexible transverse member 109. The handles 110 and 111 are suitably attached to the base 43, and are adapted for actuating said base, by the operator, either in a rotary, longitudinal or vertical direction.
- 40 In the operation of this apparatus, the fur skin 40 is placed under the band 103 upon the base 43 and firmly secured thereto by turning the handle 108 (Figure 7) in a clockwise direction, causing the protruding element 106 to force the block 104 downwardly, thereby tensioning said band 103 about said skin. The frictional engagement of said cam and the surfacing 105 holds the parts in their projected position, until released by turning the handle in a counter-clockwise direction. Once the skin is so set, the entire operation can be performed over the whole surface of same without shifting its position.
- 45 The shaft at bearing 16 is caused to rotate by a belt operating upon the pulleys 18 and 19, to cause the fly wheel 20 to rotate, thereby producing a reciprocating movement of the member 27. In this way the tool 35 is caused to operatively move along the surface of the skin in the direction of the arrow (Figure 1) for its operating stroke, the straight-line movement in a direction parallel to the surface of the base 43 being effected through properly designed members 31, 41 and 42, as hereinbefore stated.
- 50 The pressure applied by the tool is adjusted by the operator, and once so adjusted, is maintained by the lift control mechanism as follows: The rotation of the fly-wheel 20 is transmitted to the cam 21 through the pin 55, and the cam in turn actuates the roller 61, the arm 62, the hub 63 and the lift control arm 85. This motion is transmitted by the link 86 to the cam 87 which is caused to rotate until the protruding portions 120 of the surfaces of parts 87 and 89 come into engagement (Figure 5); and when this occurs, the spring 92 is compressed, thereby forcing the sleeve 91 against the wall of the framework at the opposite end, to frictionally hold said sleeve and 125 the lever 90 against movement. As the lever 90 is connected to lever 95 by the link 100, neither of these levers can move, and hence the brackets 93 and 99 are held stationary, during the operating stroke, to hold the tube 82 and consequently the entire base assembly against a lifting movement. During the return stroke, however, the depression in the cam 21 releases the follower 61 and the connected mechanism, (due to the action of spring 78a, as will be hereinafter 130

described), thereby freeing the base from its locked position and permitting the tool 35 to return to its starting position, out of engagement with the skin. Should any folds or wrinkles form on the skin, the toggle linkage will collapse, as already described, to permit the tool to pass harmlessly thereover.

It should be noted that in the unlocked position of the parts, the operator, by grasping the handles 110 and 111, can raise and lower the base at will, as the levers 90 and 95 are designed to permit a parallel movement of the lifting brackets 93 and 99.

Should the operator desire to control the blade pressure throughout the operating stroke without having a fixed and locked adjustment, he can remove the pin 112 (Figure 1), and the lift control mechanism becomes inoperative.

The base 43 can be moved either longitudinally or rotatably, by manipulating the handles 110 and 111, pushing, pulling or rotating them,—the housing 81 which supports the base being rotatably and slidably surmounted over the tube 82. In this way every portion of the skin can be reached.

During the operating stroke, the cam-actuated arm 62 causes the shaft 64 and the collar 66 to rotate, through the pins 65 and 67; and this movement is yieldably transmitted through the spring 71 and lug 69 to the rocker arm 74, thereby causing, during the operating stroke, a movement of the rod 78 in the direction of the arrow; against the action of spring 78a (Figure 3). This movement causes the central member 79 to force the wedges 80 through the opening in the tube 82 against the inner surface of the housing 81, to frictionally hold it against movement. It is hence apparent that during the operating stroke, no movement of the base is possible either in a longitudinal or a rotary direction.

Although the arm 62 may move through a considerable distance, the arm 74, being yieldably actuated by the spring 71, moves only until the wedges 80 are frictionally held in place,—any further movement of said arm 62 being taken up by said spring. It should, however, be noted that the return movement of the arm 74, and consequently the rod 78, is positive, as the nut 73 acts directly upon the lug 69 and hence on all parts immovably connected therewith, such as the arm 74. When the roller 61 is relieved of the pressure of the elevated portion of cam 21, the spring 78a, by virtue of the potential energy stored within it due to the movement of the rod 78 in the direction of the arrow (Figure 3), will expand, and force the rod 78 to move towards the right, which motion is transmitted through the link 74 and the connected mechanism to the roller 61 to return it to and yieldably hold it against the depressed portion of cam 21.

If it is desired to change the length of the stroke, the nut 57 is loosened and the notch-engaging member 53 moved within the slot to the position which will give the desired stroke. The notch-engaging member 54 must, however, also be moved within its slot a sufficient distance to bring the tool back to its original starting point. In this way the stroke can be changed without affecting the starting position. If the notches in both of said slots are in parallel alignment, the said notch engaging members should be moved through the same number of notches to get the correct corresponding positions. A corresponding and similar adjustment must be made within the slotted apertures 44 and 47, to cor-

rectly adapt its movement to the changed conditions.

It is to be noted that the tool 35 should be curved, so that there will be a leading edge during its operating movement, thereby producing cleaner and more effective results, particularly when the tool is a cutting or shaving blade. The blade should also be tilted at an angle as shown in Figure 1, to give best results.

Although a detailed embodiment of our invention has herein been disclosed and described, it is understood that other mechanical forms of our invention can be employed within the scope of the appended claims.

What we claim is:

1. An apparatus for the fleshing and scraping of fur skins comprising, in combination, a base for the support of a fur skin, a longitudinal tube associated with said base, supporting means for said base rotatably and slidably mounted over said tube, a movable mounting for said tube to permit a substantially vertical movement thereof, means associated with said base and adapted by a manipulation thereof to rotatably and slidably move said supporting means and vertically 100 actuate said tube, locking means associated with said tube to hold it and said supporting means against movement from their respective projected positions, a tool operatively movable along the surface of a fur skin supported by said base, 105 and actuating means for causing a reciprocating movement of said tool along said surface and in a direction substantially parallel to the surface of said base, said locking means being operatively connected to said actuating means.

2. In an apparatus of the class described, a base for the support of a fur skin, a tube longitudinally positioned with respect to said base; a support for said base, a cylindrical housing carrying said support and rotatably and slidably mounted over said tube, an expandable chuck within said tube, a plurality of openings in the wall of said tube, a plurality of elements in said chuck engageable with said openings and adapted to be projected therethrough for contacting with the inner surface of said housing to frictionally hold the housing against movement with respect to said tube, a chuck control rod extending within said tube and operatively connected to said chuck, and means adapted to reciprocally actuate said rod 125 within said tube.

3. In an apparatus of the class described, a base for the support of a fur skin, a tube longitudinally positioned with respect to said base, a support for said base, a cylindrical housing carrying said support and rotatably and slidably mounted over said tube, a conical member centrally positioned within said tube, a plurality of wedges circumferentially positioned about said member, a plurality of openings in the wall of said tube and adjacent said wedges, and means operable upon said member to cause it to engage said wedges and project them through said openings for contacting with the inner surface of said housing to frictionally hold said housing against movement 130 with respect to said tube; said means comprising a rod within said tube operatively connected to said conical member, a rocker arm pivotally attached to said rod, and means to actuate said rocker arm to cause a reciprocating movement 135 of said rod within said tube.

4. In an apparatus of the class described, a base for the support of a fur skin, a mounting for said base, longitudinal supporting means for said mounting, a plurality of brackets from which 150

- said supporting means depend, a plurality of levers each having one of their arms pivotally attached to one of said brackets, connecting means between the other arms of said levers, whereby the movement of one of said levers will cause a corresponding and simultaneous movement of the other levers to raise and lower said brackets, and means associated with said base and adapted by a manipulation thereof to vertically actuate
- 5 10 15 20 25 30 35 40 45 50 55 60 65 70 75
- said supporting means and one of said levers; the said supporting means comprising a longitudinal tube, a support proper for said base, a cylindrical housing carrying said support and rotatably and slidably mounted over said tube which is attached to and depends from the said brackets.
5. In an apparatus of the class described, a floatingly mounted base for the support of a fur skin, said base being rotatable about and movable horizontally along its longitudinal axis, a tool operatively movable along the surface of a fur skin supported by said base, a tool-actuating member pivotally connected to said tool, a rotatable member to which said tool-actuating member is eccentrically attached, means to actuate said rotatable member to impart a reciprocating motion to said tool-actuating member, adjusting means for detachably securing said tool-actuating member to a predetermined position on said rotatable member to vary the length of the stroke thereof, said adjusting means comprising a slotted aperture on the rotatable member and means to removably secure the rear end of said tool-actuating member at predetermined positions within said aperture; a rotatable cam operatively connected to said rotatable member, and locking means coacting with said cam to hold said base against movement during the operative stroke of said tool.
6. In an apparatus of the class described, the combination set forth in claim 5, characterized in this that the adjusting means for detachably securing the tool-actuating member to the rotatable member comprises an eccentrically positioned slotted aperture in said rotatable member and another slotted aperture within the terminal portion of said tool-actuating member, both of said apertures being adjacent each other and having notches in the walls thereof, a pin extending through both said apertures and having rotatably mounted thereover two notch-engaging members each positioned within one of said apertures and detachable means to hold said notch-engaging members in place within said apertures and against lateral movement.
7. In an apparatus of the class described, a base for the support of a fur skin, a mounting for said base, means to permit a rotatable and longitudinal movement thereof, locking means associated with said mounting to hold it against rotatable and longitudinal movement, a reciprocally actuated rod operatively connected with said locking means, a rocker arm pivotally connected to said rod and affixed to a collar loosely mounted on a rotatable shaft, a hub and a second collar being affixed to said shaft on either side of said first-mentioned collar, said collars being operatively connected by yieldable means whereby a movement of said second collar in one direction will be yieldably transmitted to said first-mentioned collar, said collars being also operatively connected by fixed means whereby the movement of said second collar in the opposite direction will be positively transmitted to the first-mentioned collar; said hub containing an outwardly extending arm, a follower pivotally attached to said arm, a cam
- operable upon said follower, and means to actuate said cam.
8. In an apparatus of the class described, a base for the support of a fur skin, a mounting for said base, longitudinal supporting means for said mounting, a plurality of brackets from which said supporting means depend, a plurality of levers each having one of their arms pivotally attached to one of said brackets, connecting means between the other arms of said levers whereby the movement of one of said levers will cause a corresponding and simultaneous movement of the other levers to raise and lower said brackets, and locking means to hold said levers against movement, said locking means comprising a rotatably mounted cam, a fixed boss on the framework of the apparatus and adjacent to said cam, the end surfaces of said cam and boss being contiguous; a rotatably mounted sleeve carrying one of said levers, an abutment adjacent one end of said sleeve, a spring between said cam and the other end of said sleeve; the said end surfaces containing complementary recesses and protruding portions, the recess of one being in engagement with the protruding portion of the other in the inoperative position of the parts, and the two protruding portions being in engagement in their operative position to compress said spring and cause it to yieldably hold said sleeve in frictional engagement with said abutment; and means to intermittently move said cam into its operative and inoperative positions.
9. In an apparatus of the class described, a base for the support of a fur skin, a tool operatively movable along the surface of a fur skin supported by said base, a tool-actuating member adapted for reciprocating movement, a bracket, a bar one end of which is pivotally mounted on the upper portion of said bracket and the other end upon the framework of the apparatus, a tool-carrying member pivotally mounted on the lower portion of said bracket, a tool secured to said tool-carrying member, the said tool-actuating member being pivotally connected to said bracket, said bracket and said bar having thereon adjustable complementary abutting elements which coact to prevent the relative outward movement of the bar, bracket and tool-carrying member beyond a predetermined point during the operative stroke; the said bar, bracket and tool-carrying member being the constituent parts of a toggle adapted to collapse inwardly on the return stroke of the tool; and operating means connected to said tool-actuating member to reciprocally actuate said toggle.
10. In an apparatus of the class described, a movable base for the support of a fur skin, a suitably mounted block underneath said base and associated therewith, a flexible band extending around said base and said block and adapted to overlie a fur skin on said base, a transverse flexible member associated with and underlying said base, a rotatably mounted cam positioned between said base and said block and having a protruding element adapted for frictional contacting with said block, a crank handle attached to said cam and frictionally engageable with said transverse member when said protruding element is in frictional engagement with said block to produce a tensioning of said band about said fur piece; and two handles associated with said base and adapted by a manipulation thereof to movably actuate said base.
